Mc. C. Burleigh, of Somersworth. N. H.
Letters Patent No. 58, dated May 28, 1861.

Whole No. 1423,

Dec. 14 23

The schedule referred to in these Letters Patent and making part of the same.

To all whom it may concern;

Be it known that I, M. C. Burleigh, of Somersworth in the County of Strafford, and State of New Hampshire, have invented or produced a new and original Design for the Doors and Panels of Stoves; and I do hereby declare that the following is a full, clear and exact description of the same reference being had to the annexed drawings making a part of this Specification, in which -

Figure 1. is a face or front view of a Stove door.

Figure 2. a section of ditto, taken in the line x.x. Figure 1.

Similar letters of reference indicate corresponding parts in the two

Figures. -

This invention relates to a new and original design for rectangular doors and panels of Stoves described as follows.

The doors and panels are of rectangular form as shown in Figure 1. and the outer edge is of curved form as shown at a. a. with an angular projection b. between them. Adjoining the inner edge of the inner curve a. there is a scrupulous surface c. of the ogee style and a plane surface d. adjoins the ogee.

The above described parts constitute the outer portion of the design. The central part is as follows:

Adjoining the inner edge of the plane surface d. there is an angular projection e. from the inner edge of which an ogee bead f. projects inward or towards the centre of the panel or plate, and centrally within this ogee f. there is a half round bead g. forming, as well as all of the other beads mentioned, a square. Within the centre of the square formed by the bead g. there is a semi-spherical projection h. -

These parts complete the design and the precise outline formed by a transverse section is shown clearly in Figure 2.

Having thus described my invention what I claim as new and desire to secure by Letters Patent, is -

The general configuration of the parts herein shown and described to form a new and original design for the doors and panels of stoves.
